[57] CLAIM

The ornamental design for a sink, as shown and described.

DESCRIPTION

FIG. 1 is a top perspective view of a sink showing my new design;

FIG. 2 is a top plan view thereof;

FIG. 3 is a bottom perspective view of the cover thereof;

FIG. 4 is a top plan view thereof with the cover removed;

FIG. 5 is a cross sectional view taken on line 5—5 of FIG. 4; and

FIG. 6 is a cross sectional view taken on line 6—6 of FIG. 4.

It is to be understood that the portion of the strainer omitted for convenience of illustration in FIGS. 4, 5 and 6 is continuous throughout the interior of the sink as indicated.

FIG. 1**FIG. 2****FIG. 3****FIG. 6**
